His Attorney.

UNITED STATES PATENT OFFICE.

WILSON B. WIGLE, OF FULLERTON, CALIFORNIA.

PUMP.

1,362,456.

Specification of Letters Patent. Patented Dec. 14, 1920.

Application filed July 26, 1918. Serial No. 246,919.

To all whom it may concern:

Be it known that I, WILSON B. WIGLE, a citizen of the United States, residing at Fullerton, in the county of Orange and State of California, have invented new and useful Improvements in Pumps, of which the following is a specification.

This invention relates to pumps, and more particularly to pumps for elevating oil from oil wells, and in turn more particularly relates to so-called liner pumps in which a detachable liner is provided to serve as the working barrel for the plunger. It is desirable in pumps of this class to frequently replace such liners as they wear and become sand-pitted and rutted or eaten away by chemical action, and the invention has for a particular object the provision and formation and combination of parts and features whereby such working barrel, together with the operating parts of the pump including the working and foot valves, may be withdrawn from the well and from their working zone in the tubing without disjointing or otherwise disturbing or breaking up the string of tubing.

The invention has for a further object the provision of parts and features of the kind mentioned so formed and interrelated that the same may be brought into and installed in working position by merely lowering the same into the tubing, by means of the pump rods, and then forcibly bringing such parts into seated operative positions responsive to a quick drop of the pump rods, and which parts and features may likewise be removed by merely elevating the pump rods, which results in dislodging the working features of the pump from their working positions in the tubing.

The invention has for further objects the provision of improved pumps and pump features of the general nature above stated, which will be superior in point of relative simplicity and inexpensiveness in construction and organization, positiveness in operation, efficiency in service, durability, convenience in use and adjustment and repair or replacement, and which will be generally superior in serviceability.

With the above and other objects in view, the invention consists in the novel and useful provision, formation, combination, association, construction and relative arrangement of parts, members and features, all

as hereinafter described, shown in the drawing and finally pointed out in claims.

In the drawing:

Figure 1 is a vertical central sectional view of pump tubing, liner or working barrel, plunger, and foot and working valves, of a pump organized in accordance with the present invention, the same being broken away transversely for convenience in illustration; 60

Fig. 2 is an enlarged detail of portions of the showing in Fig. 1; 65

Fig. 3 is a detail transverse sectional view taken upon the line x^6-x^8 , Fig. 2;

Fig. 4 is a detail sectional view, upon an enlarged scale, of features of the showing in Fig. 1 below the features shown in Fig. 2, the parts being in a slightly altered position to illustrate the mode of withdrawing the working features of the pump; and, 70

Fig. 5 is a detail transverse sectional view taken upon the line x^6-x^8 , Fig. 4. 75

Corresponding parts in all the figures are designated by the same reference characters.

Referring with particularity to the drawing, A and B designate respectively the lower and upper working valves of a pump, the same being at the respective ends of a tubular plunger 6, and all jointly supported by and connected with the pump rods, (not shown) at a coupling 7 shown at the upper end of the cage 8 of the upper working valve B. The lower working valve A likewise is confined within the cage 9. The plunger 6 operates within a liner member C 80

which fits within the well tubing D which is shown as comprising a plurality of tubing sections 10 and 11 connected by a collar 12 which is provided with a downwardly diminishing internal diameter producing a 90

choked bore as shown at 13 Figs. 1 and 2, and receiving a packing ring 14 disposed between it and the liner member C. The liner member C ranges downwardly by means of a tubular downward extension 15, to a predetermined extent, to provide the working surface to accommodate the stroke of the plunger 6; and from the upper thickened end 15^a of said liner member ranges downwardly an outer tubular section 15^b which 95

extends to the foot valve E, the same being externally threaded to the cage 16 of said foot valve, as at 16^a, such foot valve being provided with a tapered lower end portion 16^b capable of being wedged into comple- 100

105

110

mentary seat 16^a in a tubular fitting 17 threaded onto the lower end of the well tubing 11, as at 17^a. Beneath this tubular fitting 17 extends the suction pipe (not shown) through which the fluid is drawn to the foot valve, from the space above which in the working barrel, comprising the liner 15 and its extension 15^b, such fluid is elevated by the working valves A and B and 10 the plunger 6 with which they are connected.

The upper end of the liner top 15^a is formed into a sharply downwardly beveled shoulder 15^c adapted to receive the thrust 15 of the lower end of the cage 8 of the working valve B, which provides a shoulder 8^a to that end. Likewise the upper end of the cage 9 of the lower working valve A provides a shoulder 9^a to engage with the lower 20 end of the liner extension 15, at a shoulder 15^d, to serve to withdraw the liner and foot valve from the well tubing when the pump rods are elevated. In this manner the foot valve, liner 15 with its downward extension 25 15^b, working valves, and plunger 6 are all withdrawn from the tubing D, for replacement or repair of such valves or of the liner and its extension, or of the plunger 6. When these parts are lowered back into the 30 well, the packing device 14, which fits within a channel 14^a in the upper liner portion 15^a, is wedged into place, under the pressure of the shoulder 8^a upon the shoulder 15^c, as the rods are dropped; and the same dropping action forces down the foot valve E 35 into its seat 16^c at its tapered lower end 16^b, through the down-thrust of the extension 15^b of the liner. The sharply chamfered or beveled shoulder formation at 15^c prevents 40 any sand which may pass through the working valve cage 8 from getting down into the space between the upper part of the liner and the pump tubing, from working between the co-acting surfaces of the liner 45 and the plunger.

The operation, method of use and advantages of the present improvements in pumps, will be readily understood from the foregoing description and statement, taken in 50 connection with the accompanying drawing.

The working valve B is provided with an annular seat 8^b, the body of which fits down within the plunger 6 and such seat is provided with an annular shoulder 8^c which 55 overlaps the upper end of the plunger 6 and is held thereto by the cage 8, which has a matched shoulder 8^d overlying the shoulder 8^c, the threads 8^e thus serving to hold the cage and the seat both to the plunger. By 60 this formation I am thus enabled to obtain a maximum of flow through the annular seat 8^b, and also a positive and efficient assemblage of the parts.

The lower working valve and foot valve 65 disclosed in the drawing and described in the

foregoing description, are organized in accordance with the disclosure of a patent for pump valves, issued to me January 30, 1917, No. 1,214,400. While the present invention is not to be understood as to be limited in its practice to this particular organization of foot valve and lower working valve, nevertheless the same enter with high efficiency and satisfaction into the use of such present invention. 75

It is manifest that many changes and variations and modifications may be made, with respect to the structure described and shown in the drawing, in adapting the improvements to varying conditions of use and 80 service, without departing from the spirit of the invention and a fair interpretation thereof.

Having thus disclosed my invention, I claim and desire to secure by Letters Patent:

1. The combination with a tubular well casing having upper and lower seats therein, of a removable liner provided with packing means for engaging the upper seat, a tubular extension extending downwardly from the liner, a foot valve cage carried by the extension and adapted to engage the lower seat, a tubular plunger mounted to reciprocate within the liner, cages applied to the ends of the plunger and forming exterior shoulders thereon which are adapted to engage the corresponding ends of the liner for removing the liner and associated parts from the casing or placing them in position 100 when the plunger is moved beyond an ordinary pump stroke, and valves in the respective cages. 95

2. The combination with a tubular well casing having upper and lower seats therein, of a removable liner having an enlarged upper end which is provided with packing means for engaging the upper seat, a tubular extension surrounding the exterior of the liner and extending downwardly below the same, a foot valve cage applied to the lower end of the tubular extension and removably engaging the lower seat of the casing, a tubular plunger mounted to reciprocate within the liner, cages applied to the ends of the plunger, and valves in the respective cages, said cages upon the plunger providing exterior shoulders which are adapted to engage the corresponding ends of the liner for enabling the liner and associated parts to be removed from the casing or placed in position therein with the plunger. 110 105 115 120

3. The combination with a tubular well casing provided with an interior seat, of a removable liner having the upper end thereof sharply beveled, packing means upon the liner for engaging the seat of the well casing, a tubular plunger mounted to reciprocate within the liner, working valves mount- 125 130

ed upon the plunger, and a foot valve arranged within the casing in coöperative relation with the plunger and working valves, the sharply beveled upper edge of the liner 5 preventing sand and grit from working its way between the plunger and liner.

4. The combination with a tubular well casing having independent upper and lower seats therein, of a removable liner provided 10 with packing means for engaging the upper seat, a foot valve cage carried by the removable liner and adapted to engage the lower seat, a tubular plunger mounted to reciprocate within the liner, and cages ap-

plied to the ends of the plunger and forming exterior shoulders thereon which are adapted to engage the corresponding ends of the liner for removing the liner and associated parts from the casing or placing them in position therein when the plunger 20 is moved beyond an ordinary pump stroke.

In testimony whereof I have signed my name to this specification in the presence of two subscribing witnesses.

WILSON B. WIGLE.
